CLAIM

The ornamental design for a portion of a firearm handguard, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front left isometric view of a portion of a firearm handguard in accordance with the present disclosure.

FIG. 2 is a front elevation view of the portion of a firearm handguard of FIG. 1.

FIG. 3 is a rear elevation view of the portion of a firearm handguard of FIG. 1.

FIG. 4 is a right side elevation view of the portion of a firearm handguard of FIG. 1.

FIG. 5 is a left side elevation view of the portion of a firearm handguard of FIG. 1.

FIG. 6 is a top view of the portion of a firearm handguard of FIG. 1; and,

FIG. 7 is a bottom view of the portion of a firearm handguard of FIG. 1

The broken lines in the Figures illustrate portions of the article that form no part of the claimed design. The symbolic break lines shown in FIGS. 1 and 4-6 represent an indeterminate length and form no part of the claimed design.

1 Claim, 4 Drawing Sheets
